UNITED STATES PATENT OFFICE

2,682,123

ORNAMENTAL DIALER CROWN

David O. Fredrickson, Chicago, Ill., assignor to
 Clear-View Advertising Dialer Company, a cor-
 poration of Illinois

Application July 26, 1952, Serial No. 301,098

4 Claims. (Cl. 40—8)

1

This invention relates to an ornamental dialer crown for use in actuating the rotatable dial provided on automatic telephone instruments.

The object of this invention is to provide a new and improved ornamental dialer crown.

Another object of the invention is to provide an ornamental dialer crown for a handle member which may be used to attract and fix attention on a display as for advertising, such as a mechanical pencil, a letter opener, or a fountain pen.

Another object of the invention is to provide an ornamental dialer crown having a two-piece construction which may receive an advertising insert therebetween and which may be securely held together by cooperating elements of the dialer crown.

Other and further objects of the invention will be readily apparent from the following description and drawings, in which:

Fig. 1 is a perspective view showing the use of the dialer crown with an automatic dial telephone;

Fig. 2 is a front elevation of the preferred embodiment of the dialer crown with a portion of the carrying element such as a mechanical pencil cut away;

Fig. 3 is a vertical section taken along the line 3—3 of Fig. 2;

Fig. 4 is an exploded view of the dialer crown;

Fig. 5 is a horizontal section taken along the line 5—5 of Fig. 2;

Fig. 6 is a front elevation of another form of the invention with a portion of the carrying element cut away; and

Fig. 7 is a vertical section taken along the line 7—7 of Fig. 6.

While this invention is susceptible of embodiment in many different forms, there is shown in the drawings and will herein be described in detail the preferred embodiment together with a modification thereof with the understanding that the present disclosure is to be considered as an exemplification of the principles of the invention and is not intended to limit the invention to the embodiments illustrated. The scope of the invention will be pointed out in the appended claims.

A dialer crown A embodying my invention is shown in Fig. 1 mounted in a mechanical pencil B and in use as a dialer crown in cooperation with the dial portion of an automatic dial telephone C. The crown may be carried by any object which is suitable for use in dialing a telephone and is not limited to use with a mechanical pencil. Other objects such as fountain pens, let-

2

ter openers or handle members for a variety of articles would be suitable for mounting the dialer crown of this invention.

The dialer crown, in its preferred embodiment as shown in Figs. 2 to 5, comprises a two-piece construction. Each section or segment may be made out of a transparent material or one section may be made of a colored opaque material such as cellulose acetate having pigment added thereto. A plastic material such as Lucite has been found to be a good material for the transparent portion of the dialer crown since it may be molded into the desired shapes and it has the desired transparency to enable printed matter carried within the crown to be seen. The dialer crown is of a size which will engage within a finger hole on the dial telephone C.

The first section comprises a face portion 1 and a base or leg portion 2 and the second section 20 comprises a face portion 3 and a base or leg portion 4. Each of the face portions 1 and 3 are of a segmented spherical shape to provide a flat outer face 5 for a purpose set forth more fully hereinafter.

25 The face portion 3 has a generally cylindrical raised projection or flange 6 which cooperates with a generally cylindrical recess 7 in the face portion 1 to provide a space therebetween in which a printed insert 8 may be placed. The provision of flat outer faces 5 on the face portions of the dialer crown enables the printed matter carried within to be clearly seen without any distortion thereof.

Although the dimensions may vary and the following are not critical, a desirable dialer crown may be made wherein each face portion has a thickness of approximately .15 inch and the diameter of the face portions is approximately .53 inch. In this form the raised projection 6 may 35 extend above the inner surface of the face portion approximately .02 inch and the recess 7 may have a depth of .04 inch. It is thus seen that, upon assembly of the face portions 1 and 3, a space of .02 inch is provided in which may be placed a small insert of paper or other material 40 having printed matter thereon.

The projection 6 and recess 7 are of diameters 45 which will insure a tight fit therebetween. The cooperating projection and recess thus provides a suitable means for enclosing printed matter in a manner which will prevent dirt or other foreign matter reaching the insert and also securely hold the two face portions together.

Each of the leg portions 2 and 4 are lateral 55 extensions of their respective face portions 1

and 3 and provide an additional registering and locking means for the dialer crown as well as providing a means for telescopically mounting the dialer crown within a casing 9 of a mechanical pencil or any object having a generally cylindrical opening or chamber in the end thereof.

As will be clearly seen in Figs. 2 to 4, the leg portions are rounded in both directions so that, when assembled, the base of the assembled leg portions will have a generally rounded shape to facilitate insertion of the dialer crown within the cylindrical chamber 9.

The leg portion 4 has a raised generally cylindrical lug 10 which is shaped to closely fit within a generally cylindrical recess 11 provided in the leg portion 2. The lug 10 may be equal in height to the depth of the recess 11 or, as shown in Figs. 3 and 5, may extend only part way into the recess. The lug 10 and recess 11 act to register and securely lock the face portions 1 and 3 in the proper relation with respect to each other.

My new and improved dialer crown is of a construction which may be die-molded in large quantities at a low cost per unit. It is necessary to provide a structure having two parts in order to place an insert therein or to permit recessed indicia to be stamped on the inner faces of the face portions. In my invention one piece of the crown has the raised projection 6 and the lug 10 while the other piece has the recesses 7 and 11. These elements and recesses may be provided by proper shaping of the molds and no subsequent operations are required.

Another embodiment of the invention is shown in Figs. 6 and 7 wherein the dialer crown is generally similar to that shown in Figs. 2 to 5 but in which the interfitting parts on the face portions are somewhat different in their construction as are the interfitting parts on the laterally extending leg portions. Those parts in the two embodiments which are generally similar are identified by the same reference characters.

The face portion 3 has peripherally spaced raised pips or projections 12 on its inner face which engage within peripherally spaced depressions 13 in the face portion 1. The pips 12 and depressions 13 are tightly fitted together and cooperate to hold the two face portions together and against rotation relative to each other. A lug 14 on the leg portion 4 cooperates with a recess 15 in the leg portion 2 to ensure the locking of the two pieces of the dialer crown against rotation.

In this form of the invention it is preferable to provide a generally cylindrical recess 16 in one of the face portions of a depth and diameter adequate to hold an insert carrying printed matter. This recess 16 is provided in face portion 1.

The number of pips 12 and depressions 13 carried by the face portions 3 and 1, respectively, is not critical; however, it has been found that three pips with their cooperating depressions are satisfactory to securely hold the two pieces of the dialer crown together.

In this form of the invention the lug 14 and its cooperating recess 15 carried by the leg portion 2 may extend entirely across the width of the leg portion.

I claim:

1. A dialer crown mounted in a mechanical pencil or other carrier member having a cylindrical opening in the end thereof for use in dialing a telephone comprising, in combination, two

sections each having a face portion which has a segmental spherical shape and a laterally extending leg portion, at least one of said sections being transparent, one of said face portions having a substantially cylindrical raised flange thereon, the other face portion having a recess therein of a diameter to receive and tightly grip the flange, the recess being of a depth sufficient to provide a space for an insert between the base of the recess and the outer face of the flange, an insert having printed matter mounted in said recess, and one of said leg portions having a registering recess therein and the other leg portion having a lug thereon for engagement in the registering recess to register the sections and lock them against relative movement, said leg portions being adapted for mounting telescopically within the end of said mechanical pencil or other carrier member.

2. A dialer crown mounted in a mechanical pencil or other carrier member comprising, two sections each having a face portion with a flat outer face and a laterally extending leg portion adapted to fit in the pencil or other carrier member, at least one of said sections being transparent, one of said face portions having a substantially cylindrical raised flange on its inner face, the other face portion having a recess therein of a diameter to receive and tightly grip the flange, the recess being of a depth sufficient to provide a space for an insert between the base of the recess and the outer face of the flange, and means on said leg portions to register the sections and lock them against relative movement.

3. A dialer crown carried on a mechanical pencil or other implement comprising, two sections each having a face portion which has a segmented spherical shape, at least one of said sections being transparent, one of said face portions having a substantially cylindrical raised flange thereon, the other face having a recess therein of a diameter to receive and tightly grip the flange and of a depth greater than the height of the flange to provide an insert receiving space between the base of the recess and the flange, and means for attaching said face portions to a mechanical pencil or other implement.

4. A telephone dialer crown carried on a mechanical pencil or other carrier member comprising, a two-piece construction, each piece having a face portion, one of said face portions having a recess on its inner face for receiving an advertising insert and said face portions having on their adjacent surfaces cooperating interengaging means for locking the face portions together with an advertising insert therebetween, and means for securing the joined face portions to the mechanical pencil or other carrier member.
